FLOOR MOP

Filed June 26, 1928

UNITED STATES PATENT OFFICE

CHARLES SIGMOND NELSON, OF BROOKLYN, NEW YORK, ASSIGNOR TO CALEB LORING,
OF BOSTON, MASSACHUSETTS

FLOOR MOP

Application filed June 26, 1928. Serial No. 288,468.

My present invention relates to flexible frameless mops, and has for an object to provide a mop of the type known as "floor mops," but one which is equally well adapted to other uses and is characterized by an unusual degree of durability and efficiency, and one which is comparatively inexpensive to manufacture.

Mops of the class to which my invention relates have heretofore been constructed in various ways, but principally by fixing a plurality of threads of woolen or cotton yarn in a fabric backing, disposing the fabric backing upon a metal, wooden or other rigid frame, and connecting to said frame an appropriate handle. These mops are most extensively used in cleaning and polishing floors, and such use involves considerable bumping and rubbing of the fabric backing disposed upon the rigid frame against baseboards, the legs and bases of furniture, etc. The abrasion thus resulting soon causes the fabric to wear through, so that the life of such mops is relatively short, and injury to furniture incidental to their use is often considerable.

By my present invention I provide a mop which dispenses with the usual rigid frame, being constructed of materials which are flexible, pliable and self-supporting. The resulting structure is therefore sufficiently yielding and flexible to withstand to an unusual degree the bumping and rubbing against other objects incidental to the use of the mop on floors. The flexibility of the mop also renders it capable of access into corners, under low pieces of furniture and similar restricted areas. A further advantage is the saving of the cost of manufacturing and assembling a frame.

In the drawings which form part of this application for Letters Patent, and in which the same reference characters indicate corresponding parts in the several views,

Figure 1 is a perspective view, broken away at points for economy of space upon the sheet, of the mop structure after the first step in its assembling;

Fig. 2 is a perspective view, also broken

away, of the mop structure after the second step;

Fig. 3 is a cross-sectional view of the structure at a later step in its assembling;

Fig. 4 is a perspective view of one form of the completed mop; and

Figs. 5 and 6 are perspective views of modified forms of the completed mop.

In the drawings, 1 indicates a web or strip of canvas or other rather stiff, flexible material of suitable length and of a width equal to approximately twice the depth of the finished mop body as shown in Figs. 3, 4, 5, 6, and of a suitable weight. To one surface of the strip 1, along its entire length, a coating of suitable cement is applied. This cement should be insoluble in water or oil, according to the liquid with which the mop is to be used, and should be such that after hardening it will not crack and disintegrate upon flexion of the pliable fabric body. There are many suitable stock cements now commercially available for this purpose. I have used, for example, a common leather belting cement compounded of equal parts of ordinary glue and isinglass melted together after soaking ten hours, tannin being added to the resulting mixture until a soapy consistency is produced.

Upon the cemented surface of the strip 1, threads of woolen or cotton yarn 2 are laid transversely throughout half its length, leaving, however, a slight extension at the end uncovered by the yarn, as shown at 3 in Fig.

1. The remaining, uncovered half of the web or strip 1 is folded over laterally upon the yarn, as shown in Fig. 2. The ends 3 of the strip 1, with no yarn between them, are then tucked inward and cemented together to fix the yarn against ravelling out from between the confining surfaces of the web.

The resulting structure is then folded longitudinally upon itself so that the yarn ends all project in a fringe from one side of the strip 1, which thus forms a mop body member. In this form the assembly is left to dry, with the strips preferably under a slight pressure. Rows of stitching 4, 4, provide a convenient means of further securing and stiffening the body member.

It will be apparent that two separate strips, which embrace the yarn between them, may be used instead of a single strip folded upon itself, the effect in either case being to provide throughout the length of the mop body a plurality of strips securing the threads of yarn between them. It is immaterial whether or not the individual strips be joined together at their ends or edges, both forms of construction being equally within the spirit of my invention.

The structure thus obtained, which is shown in cross section in Fig. 3, is then ready to be formed into any desired shape, as for example those shown in Figs. 4, 5, 6. The form shown in Fig. 4 is designed to cover a substantially triangular area, and consists of a mop body formed into a pair of parallel portions, each of which flares outwardly at one end. Side portions are provided to connect the outer ends of the flaring portions with the other end of the parallel portions of the body to complete the mop. Fastening means, as for example rivets 5, are passed through the body to secure the side portions to the central parallel portions, and other rivets 5 secure the other ends of the side portions to the outer ends of the base portions. At a suitable point the parallel central portions are pierced by registering holes through which passes a bolt 6 carrying a ferrule 7 held upon the bolt by a wingnut 8. The handle 9 is fixed to the ferrule by any suitable means, as by the screw threads shown in the figure.

Figs. 5 and 6 illustrate modified forms of the invention. In Fig. 5 the mop body with its dependent fringe is disposed in two parallel contacting portions united by the rivets 5^a. The ends of the mop backing may be turned out at right angles from the center portion of the mop, as shown in the figure, and these ends may be held together by a bolt 6^a and wingnut 8^a adapted to receive a ferrule for attaching a handle, if desired.

Fig. 6 shows another modification, which is formed by stitching the assembly shown in Fig. 2 longitudinally down its center at 4^b, tucking in the end portions 3, 3, to prevent ravelling, folding the assembly longitudinally on itself along the stitching, and fixing the contacting parallel portions together by means of rivets 5^b. In this type of mop the bolt, ferrule and handle are dispensed with, the structure being designed and adapted to be grasped by the hand of an operator and used in place of the well known wooden or metal backed hand mop. In addition to the modifications shown, my invention is capable of embodiment in many other forms, and it is to be understood that I am not limited to the specific forms illustrated and described herein within the scope of the claim.

Having thus described my invention, what

I claim and desire to secure by Letters Patent is:

A mop devoid of a rigid frame comprising a body formed of a rather stiff flexible material and having a multiplicity of threads depending therefrom, said body being formed in two parallel portions, flaring portions disposed outwardly from one end of the parallel portions and maintained at a distance from the parallel portions by agency of the stiffness of the material alone, side portions connecting the ends of the flaring portions with the other end of the parallel portions, and fastening means in the side portions near the ends thereof securing the side portions to the parallel and flaring portions respectively.

In testimony whereof I affix my signature.

CHARLES SIGMOND NELSON.
